UNITED STATES PATENT OFFICE.

SARAH V. MARTIN, OF SAN FRANCISCO, CALIFORNIA.

LIFE-BOAT.

1,263,583.

Specification of Letters Patent. Patented Apr. 23, 1918.

Application filed February 18, 1918. Serial No. 217,796.

To all whom it may concern:

Be it known that I, SARAH V. MARTIN, a citizen of the United States, residing at San Francisco, in the county of San Francisco and State of California, have invented new and useful Improvements in Life-Boats, of which the following is a specification.

The present invention relates to improved attachments to life boats, and the object of the invention is to provide means for preventing the capsizing of a life boat when lowered into the water from the deck of a ship and also to provide, in combination with such a life boat, means which will serve as rafts, either attached to the life boat or independent thereof, and which can support a great number of persons in addition to those contained in the life boat.

In the accompanying drawing, Figure 1 is a side view of a life boat embodying my improvement; Fig. 2 is a cross sectional view thereof; Fig. 3 is a broken bottom plan view of an auxiliary safety device, detached.

Referring to the drawing, 1 indicates a life boat having secured to its sides on or below its water line hinge knuckles 2, by which and by companion hinge knuckles 3 and hinge pins 4, there are hinged to the life boat the inner edges of wooden frames or rafts 6. To the under side of said rafts 6 are secured buoys 7, which may be of any suitable character. Life lines 8 are secured around the edges of the rafts.

When the life boat is in its position of disuse on a ship, said rafts or frames hang vertically, and the buoys secured thereto are received in the cavities on opposite sides 40 of the keel below the swell in the sides of the boat. In this position they occupy space which would otherwise be unused. When

the life boat is lowered to the water, the buoys come in contact with the water before the main portion of the body of the 45 boat and they remain on the top of the water, while the life boat is descending thereto, so that the rafts swing outwardly on their hinges into a horizontal position, and absolutely prevent the boat from cap- 50 sizing.

In this position said rafts are of great assistance in insuring the stability of the boat, especially in tempestuous weather. Moreover, the life lines at their edges are 55 of great utility in saving lives which would otherwise probably be lost, as persons swimming in the water can seize hold of said life lines and support themselves thereby. When it is desired to row the life boat, the 60 rafts can be detached by removing the pintles of the hinges and then they will act as independent life rafts and will support almost, if not quite, as many persons as the life boat itself.

By my invention I not only absolutely prevent the capsizing of a life boat, which is such a common occurrence in ship wrecks, but I also provide means for saving about twice as many lives as could be saved by 70 the life boat itself without substantially increasing the space occupied by the life boat.

I claim:—

1. In combination with a life boat, buoy- 75 ant means secured to its sides and depending therefrom in the position of disuse of the life boat, and arranged to swing out horizontally from the life boat when the latter is lowered into the water.

2. In combination with a life boat, buoy- 80 ant life rafts detachably hinged to its opposite sides.

S. V. MARTIN.
